US00D686151S

(12) **United States Design Patent**
Lee et al.

(10) **Patent No.:** **US D686,151 S**
(45) **Date of Patent:** **** Jul. 16, 2013**

(54) **BATTERY**

(75) Inventors: **Jeong-Seop Lee**, Yongin-si (KR);
Myung-Sook Kwon, Yongin-si (KR);
Sang-Jin Park, Yongin-si (KR); **Nam**
Sunwoo, Seoul (KR)

(73) Assignee: **Samsung SDI Co., Ltd.**, Yongin-si (KR)

(**) Term: **14 Years**

(21) Appl. No.: **29/428,744**

(22) Filed: **Aug. 2, 2012**

(30) **Foreign Application Priority Data**

Jun. 7, 2012 (KR) 30-2012-0027969

(51) **LOC (9) Cl.** **13-02**

(52) **U.S. Cl.**

USPC **D13/103**
